LIQUID FUEL BURNING APPARATUS

Noel H. Sutterfield, Detroit, Mich., assignor to
 The Timken-Detroit Axle Company, Detroit,
 Mich., a corporation of Ohio

Application October 26, 1935, Serial No. 46,947

5 Claims. (Cl. 122—250)

This invention relates to oil burning apparatus of the type having a rotary oil and air distributing mechanism centrally located in a combustion chamber and to mechanism and apparatus to be heated thereby.

The fuel feeding, distributing and burning mechanism which I preferably employ and which is here disclosed is substantially identical with that illustrated in the copending Milton A. Powers application, Serial #740,698 filed August 20, 1934. In said application is illustrated a water heater of the tank variety, i. e., the hot products of combustion circulate around the internal surfaces of a specially constructed water tank thereby raising the temperature of any fluid contained therein.

There are many instances where home owners do not desire a unit having an integral tank as they already have a storage tank and naturally do not desire to duplicate their equipment or discard a good tank.

Therefore, a primary object of my invention is to provide a novel oil-burning, water-heating apparatus which may be used in conjunction with a water storage tank and which will maintain the water in the storage tank at a predetermined temperature.

A further object is to provide in a water heater equipped with an oil burner of the rotary wall flame type, water circulating tubes, circularly coiled adjacent the periphery of the combustion chamber and through which water is circulated. Coordinate with the feature just described, my invention also embodies means for protecting the water circulating tubes from the direct action of the flame, and yet which does not materially interfere with heat transfer to the water.

A further object is to provide an oil burning water heater wherein there is a minimum of impedance to water flow. More specifically, it is an object to provide a coil-type water heater equipped with a rotary wall flame oil burner wherein the water inlet and outlet tubes are straight and the diameter of the tube of the water tube coil is relatively large.

It is essential to the efficient operation of an oil burner, and especially a burner of the rotary wall flame type, that the quantity of air in the region of combustion be accurately controlled. Therefore, it is necessary that the combustion chamber—especially from a point slightly below to a point slightly above the vicinity of combustion origin—be air-tight in order that excess air will not be present. In prior art devices there is necessarily what is termed a fire or service and

inspection door opening into the combustion chamber at a point slightly above the zone of combustion origin. Although in most cases such doors are clamped tightly when closed, due to carelessness in closing and also wear, there is apt to be air leaks.

Therefore, a further object of my invention is to provide an oil burner combustion chamber with a fire door so located that the oil burner flame is not affected by the opening thereof.

In the case of a coil-type water heater it would be decidedly impracticable to have the service and inspection door in the usual location, for a special coil having unusual convolutions would be necessary in order to provide an aperture therein.

Therefore, a further object is to provide an oil-burning, coil-type water heater with a combination smoke hood and inspection and service door located above the water circulating coil. More specifically, it is an object to provide a coil-type water heater with a combination smoke hood and inspection and service door at the juncture of the flue and the heater casing, the flue emanating from the top of the heater.

A high stack temperature is a common fault of coil-type hot water heaters, as ordinarily the vertical length of coil over which the products of combustion pass is not sufficient to allow the transfer of the maximum of heat from the gases to the water.

Therefore a further object is to provide in an oil-burning hot-water heater having a so-called wall-flame burner, a vertically positioned, coiled water tube, the coil being located adjacent the periphery of the combustion chamber of the heater at its lower portion, and its upper portion being gradually reduced in diameter, thereby forming in effect a "bee-hive".

A further object is to provide an oil-burning coil-type hot-water heater having the coil shaped substantially as a bee-hive and a baffle plate placed on top thereof substantially closing the opening formed by the top coil, thereby compelling the hot products of combustion to pass through and around the convolution of the coil in order to pass out of the combustion chamber.

In the coil-type hot-water heaters of the prior art, there are enormous heat losses. Improved insulation has reduced these heat losses to a certain extent, but because the inside walls and top of the heater unit are directly subjected to the highly heated products of combustion it is not practical from a cost standpoint to insulate these walls to the proper degree.

Therefore a further important object of my invention is to provide a coil-type hot-water heating unit with novel means whereby the heat losses are reduced to a minimum.

5 A further object is to provide in a coil-type hot-water heater, plates spaced inwardly from the heater unit top and side walls, thereby forming insulating and/or radiating plates.

The operation of the above-mentioned plates 10 tends to increase the temperature of the portions of the oil-burning mechanism which project into the combustion chamber. Such mechanism comprises—in the rotary wall flame burner which I 15 preferably employ—the oil flinger tubes and fan head. With a fan head having air-throwing blades entirely around its periphery there is no danger of gas recirculation, for the air thrown outwardly by the blades will prevent the ingress of hot combustion gases and also will nullify the 20 effect of radiated heat. Such a fan is not practical for a water heater, however, for an economical and small capacity burner having a low oil and air rate must be employed and the fan above mentioned would not provide the desired 25 characteristics. Therefore it is necessary that a fan having only a few working blades be employed. Prior art fans of this nature have a few diametrically opposite working blades and a circular skirt therebetween, inside of which is a low 30 pressure area by reason of the blades there-adjacent pulling air therefrom. Recirculated combustion gases are sucked under the fan in this region which heat the flinger tubes and cause carbon to collect therein. The recirculated 35 gases also heat up the burner mechanism below the combustion chamber which often results in damage to the parts.

The above and further objects will become apparent from a study of the following description 40 when considered with the accompanying drawings, wherein:

Figure 1 is a front elevational view partly broken away, of the hot water heating unit of my invention,

45 Figure 2 is a side elevational view of Figure 1 but is reduced in scale.

Figure 3 is a sectional view taken substantially along the line 3—3 of Figure 1, looking in the direction of the arrows,

50 Figure 4 is a partial sectional view, taken substantially along the line 4—4 of Figure 3.

Figure 5 is an enlarged sectional view of the base of Figure 2, and is taken substantially along the line 5—5 of Figure 2.

55 Figure 6 is a plan view, partly broken away, of the fan of Figure 4.

Figure 7 is a sectional view of Figure 6 and is taken substantially along the line 7—7, and

Figure 8 is a sectional view taken substantially 60 along the line 8—8 of Figure 6.

Referring now to the drawings, wherein like reference characters refer to like parts throughout the several figures, and with particular reference to Figures 1, 2, 3, 4 and 5, the oil-burning 65 water heater of my invention comprises a base member 1 which supports an upper structure generally designated as 3. Base member 1 is preferably made of sheet metal and comprises a supporting member 5, a cover 7 and a ring 11. Member 5 is substantially cylindrical in shape, having 70 one side thereof open and terminating in outwardly extending parallel walls 13. A plurality of anchoring brackets 14 are suitably secured to the lower inner side of cylindrical portions and 75 are for the purpose of positioning the unit with

respect to a flooring. Circular ring 11 is provided with an upstanding rim portion 15 which fits into and is secured to the cylindrical portion of supporting member 5 by suitable means such as spot-welding.

5 The inner portion of ring 11 terminates in a downwardly extending circular portion or flange 17, the height of which varies uniformly from a minimum to a maximum, said minimum and maximum heights being opposite diametrically, 10 as seen in Figure 4, the result being to tilt the hearth assembly in the manner to be hereinafter pointed out. Attached to the lower portion of ring 11 outwardly of downwardly extending portion 17 is a series of bolts 19, the heads of which 15 are secured to the underside of the ring by suitable means such as spot-welding. Bolts 19 are adapted to support a lower hearth plate 21 and an insulating plate 23. The insulating plate is clamped between the lower edge of flange 17 of 20 ring 11 and lower hearth plate 21. Due to the graduated lower edge of flange 17, the lower hearth plate and insulation plate are secured in said base member 1 in a sloping position. The reason for the slope is to assist in draining over- 25 flow oil, as fully set out in the above-noted Powers application, and as this part of the structure is not claimed herein it will not be further described.

Cover 7 is substantially U-shaped, the legs of the U registering with and fitting about the parallel portions 13 of member 5 and the bottom of the U having ventilating louvres protruding therefrom. Said cover 7 is also provided with a top portion.

With cover 7 removed, an opening is provided 35 through which the oil burner mechanisms may be inserted and installed and which are more fully described in the above-noted copending Powers application. Suffice it to say that the oil burner mechanism comprises an ignition 40 transformer 25, a constant level oil valve 27, a drip bucket and automatic shut off mechanism 29, a burner motor 31, the latter driving a distributor head comprising oil flinger tubes 33 and an air fan 35, the fan assembly, however, forms 45 part of this invention.

The hearth structure comprises an upper hearth plate 37 suitably spaced from lower hearth plate 21 and insulating plate 23 and has mounted thereon, preferably in sealing relationship therewith, an upstanding air deflecting ring 39, a second upstanding ring 41 of greater diameter and height than ring 39, and a third upstanding ring 43 of even greater diameter and height than ring 41. Mounted on top of the ring 41— 50 which will hereinafter be termed impact ring—is a series of grills G which are more fully described in the James A. Wilson copending application Serial No. 682,374, filed July 27, 1933. In the interest of clarity only a few grills are illustrated, 55 but it is to be understood that said grills are continuous around the periphery of impact ring 41.

Intermediate upper hearth plate 37 and lower hearth plate 21 is a radiation plate 45 suitably supported upon and spaced from lower hearth plate 21 by means of lips 47 bent downwardly from plate 45. The radiation plate is of slightly less diameter than the inside of outwardly extending portion 17 of ring 11.

70 The inside of upper structure 3 is formed by two semi-cylindrical members 49 joined together at their ends by suitable means such as screws 51 to form a cylindrical section. Spaced inwardly from members 49 is a cylindrical insulating or 75

radiating shield 53 formed of mating halves joined together. Provided in shield 53, at spaced points of its height, are circular raised portions or corrugations 55, which strengthen it and also insure a uniform spacing thereof from members 49. The lower portions of members 49 rest upon the upper surface of ring 11 as does also shield 53. Spaced outwardly from cylindrical members 49, and having its lower margin resting upon the upper portion of the upturned portion 15 of ring 11, is a metal cover or casing 61 of cylindrical configuration. Suitable insulation 57 fills the space between member 49 and cover 61.

Resting upon the upper portion of members 49 is a circular plate 63 having a central circular aperture therethrough. Fitting in the aperture of plate 63 and attached thereto by means of an angular member 65, is a cylindrical flue member 67. Placed on top of plate 63 is top insulation 69 and resting upon the upper portion of said insulation is a top metallic cover 71 having a downwardly-turned periphery which fits over the top portion of casing 61. Removably secured to flue member 67 by suitable means, such as bolts, is a flue casting member 73 having on the back side thereof a circular sleeve-like portion 75 adapted to receive suitable piping, and on its opposite side a slanting combination smoke hood, and inspection and service door 77. The inspection door 77 is provided with suitable means to normally keep it in closed position.

Supported on the underside of top plate 63, and spaced therefrom by suitable means such as screws 79, is a top insulating and radiating plate 81. Plate 81 is suitably secured to the lower margin of flue member 67 by means of an angle member 83. On the forward side of cover 61 is secured a substantially U-section plate 85 having substantially centrally thereof a manual heater on and off switch 87 which forms no part of this invention.

Inside of insulating shield 53 is a preferably single continuous coil 89 preferably of copper, which is supported in fixed relation to the burner and casing parts by means of one end thereof fitting within an inlet casting 91 and the other end thereof fitting within an outlet casting 93. Castings 91 and 93 project in preferably parallel relationship through the walls of said heater on opposite sides, the inlet casting being adjacent the lower portion and the outlet casting being adjacent the upper portion. The inlet and outlet castings are removably secured to semi-cylindrical members 49 by suitable means such as bolts (not shown). It should be observed that both the inlet and outlet connections are straight, thereby presenting a minimum impedance to fluid flow. Accordingly, the convection currents established by the heat of combustion may rapidly flow through the coil.

The diameter of the tubing of coil 89 is relatively large, thereby providing rapid circulation, due to less friction and a greater heat transfer due to a greater temperature difference. Tubes 89 are of sufficient size and thickness to be self-supporting from their two points of suspension; however, if desired, other supports may be provided. The lowermost convolution of the coil structure is spaced above lower insulating plate 45 and is disposed between upstanding ring 43 of the hearth assembly and cylindrical insulating plate 53. Coil 89 extends upwardly for the greater portion of its length in cylindrical fashion; however, the top few coils are of successively decreased diameter, thereby forming in effect a bee-hive ar-

rangement. A removable baffle plate 95 is placed over the opening left by the top coil, to compel the rising gases of combustion to circulate out through the upper coils.

In operation, inlet and outlet members 91 and 93 will be connected to a storage tank and the storage tank supplied with water as needed. When the temperature of the storage tank reaches a certain predetermined "low" temperature, the burner mechanism will be automatically started, through the action of suitable mechanism contained in the storage tank, and the coil 89 will be heated by the combustion gases.

As previously noted, I preferably employ a burner of the rotary wall flame type, and therefore the flame of the burner will be adjacent upstanding ring 43. The lowermost coils of coil 89 will be subjected to radiated heat from upstanding ring 43 and also from lower plate 45 as well as circulated combustion gases. The upper coils of said coil 89 will be subjected directly to the hot products of combustion. The combustion gases will tend to pass over the inner sides of said coil, and were it not for the bee-hive shape and baffle plate 95 they would pass directly up through the flue. However, with the bee-hive shape, and with baffle plate 95, the combustion gases are forced to circulate around and through the coils 89 in order to escape through the flue. Therefore, the entire surface of the coils is contacted by the hot products of combustion, thereby extracting as much heat as possible therefrom and also reducing the stack temperature. The insulating plates 45, 53 and 81 radiate heat absorbed thereby back toward the coils and thus further increase the efficiency of the unit. In addition to this function, the shields, due to their being spaced from the sides, top and bottom of said unit, prevent a large portion of heat from reaching the insulation.

Referring now to Figures 6, 7 and 8, the fan 35 I preferably employ for the oil burner best adapted for my unit, and which forms part of this invention, has a cup-shaped cover portion 97, the sides of the cup terminating in a slightly outwardly extending lip 99. The side of the cup is provided with diametrically opposite openings 101. Attached to the underside of cover 97 and extending through openings 101 are a plurality of fan blades 103. The blades are secured to the underside of cover 97 as by spot-welding bent portions thereof to the cover. Blades 103 are notched as at 107 on their lower inner portion for the purpose of clearance, and they extend outwardly beyond the outer periphery of cover 97. Flinger tubes 33 are disposed to one side of each pair of long blades 103, but preferably terminate short of the flange of the cover of the fan as indicated by the dotted lines in Figure 6.

Intermediate fan blades 103, and disposed inside of the skirted portion of cover 97 are shorter blades 109. Blades 109 are formed with notches 111 similar to the notches 107 of blades 103, but they terminate inside of the skirted portion. Blades 109 are secured to the underside of cover 97 in the same manner as are blades 103.

Blades 103 are the only ones that are working blades in the sense that they are the only ones which propel air outwardly from said fan for supplying the carbureted fuel at the periphery of the hearth with combustion air. Therefore, blades 109 are non-working blades. Blades 109, however, have the definite function of preventing any combustion air or gases from entering under the skirted portion of cover 97 during rotation

of the fan. Recirculation gases will, of course, not enter through cover openings 101 as air is being forced outwardly therethrough by means of working blades 103. Therefore, the flinger tubes 33, which extend along blades 103, will be protected from the hot recirculation gases and the effect of radiated heat, and will only be contacted by cool air which is drawn upwardly through the opening provided therefor in the lower portion of the combustion chamber and propelled outwardly by means of working blades 103. Therefore, the flinger tubes will be maintained free of carbon and the motor and other parts of the burner will be protected from the heat of the combustion chamber.

Operation

Assuming that motor 31 is operating and the distributor is throwing a substantially horizontally disposed sheet of comparatively large, unatomized droplets of oil toward ring 41, and that fan 97 is simultaneously discharging a blast of air downwardly and outwardly over hearth plate 31, over deflecting wall or ring 39, and through grills G, combustion is initiated by any suitable means located in the gutter formed by rings 39 and 41 (not shown). After combustion has been initiated and has propagated around the rings, ring 41 is promptly heated to a temperature sufficiently high to substantially instantaneously volatilize all of the fuel impinging thereagainst, with the result that the flame rises above the grills. The flame is directed outwardly from the grills against ring 43, substantially as shown in Figure 4, with the result that ring 43 is heated to a high temperature and radiates heat from its outer surface into the lower heater coils. A part of this radiated heat is transmitted to plate 53 and is then reflected back to the coil. The hot products of combustion rise above the grills and circulate about the upper convolutions of the coil before leaving the chamber by way of flue 13, as previously pointed out. Ring 41 is continuously maintained at the volatilizing temperature of the fuel by a part of the heated products of combustion circulating behind it, as indicated in Figure 4. Therefore, as ring 43 prevents these circulating products of combustion from directly contacting the lower parts of the coil, which contain comparatively cold water and which are of a material which conducts heat rapidly, member 43 is maintained at a comparatively high temperature and possible condensation of liquid fuel upon the lower convolutions of the coil is precluded.

While the device is operating as just described, heat from the burning gases of combustion is radiated outwardly against lining 53, which reflects the heat waves back against the coil. In this way the heat generated in the device is efficiently transmitted to the water. A part of the heat is radiated downwardly onto fan 97, but the cool air currents passing therethrough serve to keep the same at a comparatively low temperature. Also, by reason of the long and short fan blades, the outflow of air from the fan precludes the possibility of combustion gases entering under the fan skirt and heating and "carbonizing" the flinger tubes. Also radiator plate 45 reflects radiated heat upwardly and assists insulation 23 and plate 21 to keep the motor and the other mechanism located in the base at a comparatively low, safe temperature.

From the above and foregoing description, it is evident that I have provided a water heating

unit which may be used in connection with any storage tank and which is highly efficient because of the radiation plates and the novel coil formation, as well as the large diameter tubing and the absence of abrupt changes in direction of fluid flow. It is further evident that I have provided a fan for the burner of such a unit which will be conducive to greater over-all efficiency of the unit in that it effectively seals the burner mechanism from the high temperatures of the combustion chamber.

While I have illustrated and described my invention as being for a hot water heater it is evident that it may be used as a furnace for a hot water heating system, or a flash boiler for a steam heating system, and therefore the term "water heating coil" in the appended claims is intended to embrace the coils of heating systems, flash boilers and the like.

The invention may be embodied in other specific forms without departing from the spirit or essential characteristics thereof. The present embodiment is therefore to be considered in all respects as illustrative and not restrictive, the scope of the invention being indicated by the appended claims rather than the foregoing description, and all changes which come within the meaning and range of equivalency of the claims are therefore intended to be embraced therein.

What is desired to be secured by United States Letters Patent is:—

1. In a water heating device, a wall structure defining a substantially upright combustion chamber, a water-heating coil disposed in said chamber and located adjacent the walls thereof, a substantially centrally disposed liquid fuel burning apparatus mounted in the lower end of said chamber and comprising a central means for projecting a blast of air and a horizontal sheet of unatomized oil outwardly, an upright metallic impact member spaced inwardly from the walls of said chamber against which said oil is adapted to impinge and over which said air is adapted to flow, said oil atomizing against said impact member and combusting with said air above and outwardly of said impact member, to thereby maintain the latter at a temperature sufficiently high to volatilize oil impinging thereagainst, and a generally annular upright baffle disposed in said chamber between the lower end of said coil and said impact member for precluding direct contact of the combustion gases with the lower end of said coil.

2. The device described in claim 1, wherein said baffle is disposed closely adjacent the lower end of said coil and is constructed of comparatively thin metal whereby it will be heated to a high temperature and will transmit heat by radiation to said coil.

3. The device described in claim 1, wherein said chamber is provided with a hearth floor, and said baffle seats in sealing engagement therewith to prevent oil from leaking therebetween.

4. In a water-heating device, a wall structure defining a substantially upright combustion chamber, a water heating coil disposed in said chamber and comprising substantially vertically aligned closely spaced convolutions located adjacent the walls thereof, a substantially centrally disposed liquid fuel burning apparatus mounted in the lower end of said chamber and comprising a central means for projecting a blast of air and a horizontal sheet of unatomized oil outwardly, an upright metallic impact member spaced inwardly from the walls of said chamber against

- which said oil is adapted to impinge and over which said air is adapted to flow, said oil atomizing against said impact member and combusting with said air above and outwardly of said impact member, to thereby maintain the latter at a temperature sufficiently high to volatilize the oil impinging thereagainst, and a generally annular upright baffle disposed in said chamber between the lower end of said coil and said impact member for precluding direct contact of the combustion gases with the lower end of said coil, the convolutions of said coil providing an upright walled combustion space, the upper convolutions of said coil, at a vertical distance approximately equal to the diameter of said combustion space, sharply decreasing in diameter and forming a wall of beehive configuration having a partially closed top providing a restricted gas outlet, and also providing a radiant heat absorbing roof for said combustion space, for bringing about an efficient heat transfer to said coil.
5. In a water-heating device, a wall structure defining a substantially upright combustion chamber, a water-heating coil disposed in said chamber and comprising substantially vertically aligned closely spaced convolutions located adjacent the walls thereof, a substantially centrally disposed liquid fuel burning apparatus mounted in the lower end of said chamber and comprising a central means for projecting a blast of air and a horizontal sheet of unatomized fuel outwardly, an upright metallic impact member spaced inwardly from the walls of said chamber against which said oil is adapted to impinge and over which the air is adapted to flow, said oil atomizing against said impact member and combusting with said air above and outwardly of said impact member, to thereby maintain the latter at a temperature sufficiently high to volatilize the fuel impinging thereagainst; and a generally annular upright baffle disposed in said chamber between the lower end of said coil and said impact member for precluding direct contact of the combustion gases with the lower end of said coil, the convolutions of said coil providing an upright unbroken-walled combustion space, said wall structure having an apertured top, a flue pipe connection mounted on said top in alignment with said aperture and having a door therein through which access may be gained to said central means for projecting a blast of air and unatomized oil.

NOEL H. SUTTERFIELD.
